US00D991357S

(12) **United States Design Patent** (10) **Patent No.:** **US D991,357 S**
(45) **Date of Patent:** **** Jul. 4, 2023**

(54) **GOLF CLUB HEAD**

(71) Applicant: **PARSONS XTREME GOLF, LLC**,
Scottsdale, AZ (US)

(72) Inventor: **Caleb S. Kroloff**, Phoenix, AZ (US)

(73) Assignee: **PARSONS XTREME GOLF, LLC**,
Scottsdale, AZ (US)

(**) Term: **15 Years**

(21) Appl. No.: **29/807,819**

(22) Filed: **Sep. 15, 2021**

Related U.S. Application Data

(63) Continuation-in-part of application No. 29/797,375,
filed on Jun. 30, 2021.

(51) **LOC (14) Cl.** **21-02**

(52) **U.S. Cl.**
USPC **D21/759**

(58) **Field of Classification Search**
